UNITED STATES PATENT OFFICE.

WILLIAM KARL LEWIS, OF OMAHA, NEBRASKA.

OIL BURNER.

Application filed February 13, 1922. Serial No. 536,127.

To all whom it may concern:

Be it known that I, WILLIAM K. LEWIS, a citizen of the United States, and resident of Omaha, in the county of Douglas and State 5 of Nebraska, have invented certain new and useful Improvements in Oil Burners, of which the following is a specification.

This invention relates to oil burners and it consists in the combinations, constructions and arrangements herein described and 10 claimed.

An object of my invention is to provide a burner of simplified construction which is adapted to be arranged within furnaces 15 and heating plants originally constructed for the use of coal or the like as a fuel therefor, whereby hydrocarbon fuel, such as various grades of oils, may be used as fuel for such furnaces and heating plants without 20 any extensive changes, if any, in the ordinary construction of the latter being required.

A further object of my invention is to provide a furnace which is constructed in such manner as to direct the flame occasioned by the combustion of a fuel therein 25 radially of the burner, thereby insuring the diffusion of the heat generated over a maximum area and thus effecting an economy in the use of fuel.

30 A further object of my invention is to provide facilities for supplying steam or intermingled steam and water vapors to a burning hydrocarbon fuel, thereby aiding in the accomplishment of practically complete 35 consumption of the fuel and preventing the accumulatiton of carbon deposits.

Other objects and advantages will be apparent from the following description and the novel features of the invention will be 40 particularly outlined in the appended claims.

My invention is illustrated in the accompanying drawing forming a part of this application in which

45 Figure 1 is a vertical section through a portion of a furnace and through an embodiment of the invention applied thereto, and

50 Figure 2 is a perspective view of the embodiment of the invention detached from the furnace.

In carrying out my invention, I provide a substantially pan-shaped base which comprises a flat bottom portion 1 having a relatively 55 large central opening 2 formed therethrough and being provided at its outer edge

with an upstanding continuous flange or side portion 3 which is preferably formed integrally with the bottom 1. A hollow burner body 4 is upstanding from the central opening through the bottom 1 and is joined at its lower end to the inner wall of the latter. 60

The burner body 4 has side walls which flare outwardly in a uniform manner from the lower end to the upper end thereof and which are joined to at their upper ends or formed integrally with an inwardly and upwardly inclined flange or rib portion 5 which supports a top or closure 6. The top or cover or closure 6 may be formed integrally with the flange 5 or separately and 70 secured upon the latter, as may be desired.

The burner body 4 has a plurality of peripheral series of openings formed to extend radially through its walls in different horizontal planes. The series of openings are respectively indicated at 7 to 13 inclusive. The openings of the respective series vary in size from the lowermost series 7 which is located in a plane above that of the 80 bottom 1 and below that of the upper edge of the marginal flange 3, to the uppermost series 13 which lies in a plane adjacent to that of the lower end of the inclined flange 5 and which comprises openings of the 85 largest size.

Openings 14 are formed through the bottom 1 at diametrically opposite points and intermediately of the inner and outer edges thereof. In practice, the base 1 is superimposed upon grate bars 15 which are arranged within a furnace or heater between the fire pot and ash pit portions 16 and 17 of the furnace or heater, whereby the marginal flange 3 is spaced from the inner wall of 90 the fire pot portion of the heater. An asbestos composition or other suitable refractory material is arranged between the base 1 and the inner wall of the fire pot so that

95 ascending currents of air within the ash pit are deflected into the open lower end of the body 4. Branch fuel supply conduits 19 have their discharge ends projected through the openings 14 to a plane slightly above the plane of the bottom 1 and in such manner as to have a fluid tight fit with the opening. The branch conduits 19—19 are controlled by valves 20 connected therewith and are joined by a suitable pipe fitting, such as the T 21 with a main fuel supply conduit 110 22 leading to a source of fuel supply, not shown. The source of fuel supply is prefer-

ably located above the level of the bottom 1 although fuel may be forced therethrough by pressure means such as are well known in the art. A conduit 23 which is adapted 5 for connection with a source of water supply not shown, has the discharge end thereof extending through the top 6 to depend within the body 4. The conduit 23 has a suitable arrangement 24 which may be of any 10 known type of construction for controlling the flow of water therefrom and for causing the same to be discharged at a desired rate, in the form of a spray, which will be converted into steam immediately upon striking 15 the heated wall of the burner.

From the foregoing description of the various parts of the device, the operation thereof may be readily understood. It will be understood that the burner is made of any 20 suitable material, such as cast iron. A suitable hydrocarbon fuel, such as kerosene is supplied by the conduit 19 to the base and will accumulate upon the latter between the flange 3 and the lower end portion of the 25 body 4. The hydrocarbon fuel delivered to the base will be ignited when a desired quantity has been discharged from the conduit 19 and is confined between the flange 3 and the portion of the body 4 below the level 30 of the lowermost series of openings 7. The currents of air passing into the body 4 from the fire pit will be deflected radially through the several series of openings and will not only promote combustion within the base 35 but will force the frame radially or laterally of the body 4 to impinge against the wall of the fire pot, thereby insuring the radiation from the furnace or heater equipped with my invention of practically all the 40 heat developed by the combustion of a given quantity of fuel. The steam from the conduit 23 is entrained with the air currents and deflected upon the surface of the burning oil, thereby aiding in breaking up 45 masses of oil and in occasioning the practically complete consumption of the oil delivered to the burner. An important feature of the invention is the provision of 50 spaced series of openings of different sizes, the openings of the uppermost series being the largest, whereby the volume of the air currents passing through the openings of the uppermost series is greater than that of the air currents passing through the openings of a lower series. Consequently, the 55 flame will be deflected outwardly until the same has attained a height considerably greater than that of the burner body 4 and thus practically all the heat developed will 60 be utilized in heating the walls of the furnace and will not be wasted, as by being drawn directly through a flue of the furnace. The flaring form of the burner body 4 produces an advantage in that the currents 65 of air passing through the openings of the

respective series are deflected downwardly and thus promote combustion of the oil discharged upon the pan-shaped base.

Obviously my invention is susceptible of embodiment in forms other than that illustrated in the accompanying drawing and I therefore consider as my own all modifications and adaptations of the form of the device disclosed herein which do not depart from the spirit and scope of the invention 75 as outlined in the appended claims.

I claim:—

1. In a burner, a base consisting of a bottom having a central opening formed therethrough and an upstanding flange at its outer edge, and a hollow body upstanding from the central opening through said bottom and being provided with a plurality of openings through its side walls, said hollow body being formed to flare outwardly toward its upper end, the side walls of the body being concavely curved from their lower to their upper ends.

2. In a burner, a base consisting of a bottom having a central opening formed therethrough and an upstanding flange at its outer edge, and a hollow body upstanding from the central opening through said bottom and being provided with a plurality of openings through its side walls, said hollow body being formed to flare outwardly toward its upper end, the side walls of the body being concavely curved from their lower to their upper ends and being closed at its upper end.

3. In a burner, a base comprising a flat bottom having a relatively large central opening formed therethrough and having an upstanding marginal flange at its outer edge, and a hollow body upstanding from the central opening through the bottom of the base and being formed to flare outwardly toward its upper end, said hollow body being closed at its upper end and having a plurality of spaced peripheral series of openings formed through its walls, the openings of certain of said series being larger than the openings of other series and being directed downwardly and outwardly toward their outer ends.

4. In a burner, a base comprising a flat bottom having a relatively large central opening formed therethrough and having an upstanding marginal flange at its outer edge, and a hollow body upstanding from the central opening through the bottom of the base and being formed to flare outwardly toward its upper end, said hollow body being closed at its upper end and having a plurality of spaced peripheral series of openings formed through its walls, the openings of certain of said series being larger than the openings of other series, the uppermost of said series comprising openings of the largest size and the lowermost of said series

comprising openings of the smallest size, said openings being directed downwardly and outwardly toward their outer ends.

5. A burner comprising a base consisting of a flat bottom having a relatively large central opening, formed through its walls and an upstanding marginal flange at its outer edge, said bottom being provided with an inlet opening, a hollow body upstanding 10 from the central opening and being provided with openings through its side walls, said openings being directed downwardly and outwardly toward their outer ends and means communicating with said inlet for 15 discharging a hydro-carbon fuel upon said bottom within the space between said marginal flange and said body.

6. A burner comprising a base consisting of a flat bottom having a relatively large 20 central opening, formed through its walls and an upstanding marginal flange at its outer edge, said bottom having inlet openings formed therethrough at diametrically opposite points, a hollow body upstanding

from said central opening and having its 25 side walls concavely curved in longitudinal sectional contour and openings formed through the side walls, said openings being directed downwardly and outwardly toward their outer ends, and means connecting with 30 said inlet openings for discharging a hydro-carbon fuel upon said bottom.

7. A burner comprising a base consisting of a flat bottom having a relatively large 35 central opening, formed through its walls and an upstanding marginal flange at its outer edge, said bottom having inlet openings formed therethrough at diametrically opposite points, a hollow body upstanding from said central opening and having openings 40 formed through the side walls thereof, means connecting with said inlet openings for discharging a hydrocarbon fuel upon said bottom, and a conduit having a discharge end pendant within the hollow body 45 and being adapted to discharge a fluid against the inner walls of the latter.

WILLIAM KARL LEWIS.
